CLAIM

The ornamental design for a combined container/bottle and cosmetic wand applicators or the like, as shown and described.

DESCRIPTION

FIG. 1 is an exploded front elevational view of a "combined container/bottle and cosmetic wand applicators or the like", showing our new design;

FIG. 2 is a rear elevational view thereof with applicator caps on;

FIG. 3 is a side elevational view of FIG. 1;

FIG. 4 is a partially exploded side elevational view

showing a second embodiment of our new design wherein the applicator caps have been modified; FIG. 5 is a top plan view of FIG. 1, with applicator caps removed;

FIG. 6 is a bottom plan view thereof, with applicator cap removed;

FIG. 7 is an exploded front elevational view of a "combined container/bottle and cosmetic wand applicators or the like", showing a third embodiment of our new design;

FIG. 8 is a rear elevational view thereof with applicator caps on;

FIG. 9 is a side elevational view of FIG. 7;

FIG. 10 is a partially exploded side elevational view showing a fourth embodiment of our new design wherein the applicator caps have been modified;

FIG. 11 is a top plan view of FIG. 7, with applicator caps removed;

FIG. 12 is a bottom plan view thereof, with applicator cap removed;

FIG. 13 is another exploded front elevational view of a "combined container/bottle and cosmetic wand applicators or the like", showing a fifth embodiment of our new design;

FIG. 14 is a rear elevational view thereof with applicator caps on;

FIG. 15 is a side elevational view of FIG. 13;

FIG. 16 is a partially exploded side elevational view showing a sixth embodiment of our new design wherein the applicator caps have been modified;

FIG. 17 is a top plan view of FIG. 13, with applicator caps removed;

FIG. 18 is a bottom plan view thereof with applicator cap removed;

FIG. 19 is an exploded front elevational view of a "combined container/bottle and cosmetic wand applicators or the like", showing a seventh embodiment of our new design;

FIG. 20 is a rear elevational view thereof with applicator caps on;

FIG. 21 is a side elevational view of FIG. 19;

FIG. 22 is a partially exploded side elevational view showing an eighth embodiment of our new design wherein the applicator caps have been modified;

FIG. 23 is a top plan view of FIG. 19, with applicator caps removed; and

FIG. 24 is a bottom plan view thereof with applicator cap removed.
